surfaces and stated attorney's widow, Miss O'Brien, has agreed to allow the Board of Regents of the Carnegie Institution of Washington to conduct special researches in connection with the development of the invention. The Board of Regents has agreed to make available to the Carnegie Institution of Washington all information or data of a technical nature which may be developed in connection with the invention.

UNITED STATES PATENT OFFICE

RECEIVED
JULY 13 1948
CROWN BOTTLE CAP

Robert P. Smith, Crawfordsville, Ind., assignor to
The Hoosier Crown Corporation, Crawfordsville, Ind., a corporation of Indiana

Application August 13, 1941, Serial No. 406,581

1 Claim. (Cl. 215—39)

This invention relates to a bottle crown or crown bottle cap as it is sometimes designated, and relates particularly to a novel structure which eliminates the use of the heretofore employed cork liner or composition cork liner and which also permits the use of black iron in place of the commonly heretofore employed tinned iron.

Due to the present war conditions, it has become increasing difficult to obtain cork for use in the crown liners and the beverage bottling industry is confronted with the problem of either finding some substitute, some different manner of sealing the glass beverage bottles or discontinuing business.

As above indicated, it is a primary object of the invention to provide a structure wherein glass bottles may be sealed in the absence of a cork liner by a crown and the invention even goes further in that the crown itself may be made out of black iron instead of having to be tin coated. Tin is also one of the materials the supply of which is seriously affected in the present world crisis, particularly for use in non-defense articles.

A still further primary object of the invention is to provide a structure of the nature above indicated wherein the application of the crown to the bottle results in a seal more perfect than has been obtained heretofore with the use of the cork insert. In this regard, it has heretofore been a common practice to create the seal between the crown and the bottle by compressing the cork insert directly against the upper end of the bottle. It so happens that the end part of the bottle is that part which is subject to shrinkage and change in shape as the glass is formed and cooled in the molding process. The present invention embodies a sealing between the crown and the outer circumferential part of the bead provided around the mouth of the bottle since this portion of the bead is formed within the mold and is quite uniform in contour and dimensions, all of which means that a very important advantage is obtained by the present invention in that the number of "rejects" discovered on test following the crowning operation are materially reduced and in fact reduced to a negligible quantity.

Another important object of the invention is to provide a crown structure of the above indicated nature which may be produced and applied at a relatively low cost, and in fact at a cost ultimately not exceeding that of the heretofore cork-lined crown. Another advantage is that

the cost of the invention is limited to that of the metal and to whatever is the cost of the adhesive used in bonding the liner to the crown.

Another advantage of the invention is that it is a simple liner and it is economical of material.

Another advantage of the invention is that it is a simple liner and it is economical of material.

Another advantage of the invention is that it is a simple liner and it is economical of material.

Another advantage of the invention is that it is a simple liner and it is economical of material.

Another advantage of the invention is that it is a simple liner and it is economical of material.

suitable fiber or cellulose derivative, all to have a degree of resilience. As an example of one particular structure, a fifteen point board is selected to which is laminated in the usual manner a sixty pound sheet of similar material with a substantially smooth outer surface. The sheet may be processed before or after laminating with the board with a suitable sizer, such as a casein product. Then this sheet side of the paper is coated with a hydrogenated rubber derivative which is combined with natural or synthetic resins, oils, waxes, or the like, to form a flexible and vapor-resistant coating over the paper in the neighborhood of a minimum of one millimeter in thickness. The proportion of the rubber derivative in the coating compound may vary from five to ninety-five per cent of the compound depending upon the other materials employed, the use to which the crown is to be put (that is, the nature of the bottle contents), and the desired thickness of coating. The rubber derivative is roller coated on the paper commercially and is then dried. The coating may be allowed to dry at room temperature but application of heat will reduce the drying period considerably. The minimum quantity of coating is approximately $2\frac{1}{4}$ pounds to 2880 square feet of paper surface. The coating, of course, may be pigmented if desired.

As above indicated, the paper liner 11 extends entirely around and down to the undercut edge of the crown and the paper may be sealed across its edge with the cut edge of the metal of the crown by any suitable material, such as one of the many available lacquers. This is particularly advantageous when the crown metal is not tinned and is therefore subject to rusting. The lacquer seal will prevent entrance of moisture or liquids between the paper and the metal at this line. Even though the metal of the crown be tinned, obviously the cut edge will expose the base iron leaving an untinned raw edge, and again the seal will coat over this raw edge to prevent a rust line from appearing.

Now referring to Fig. 3, a crown formed as above indicated is shown applied over the mouth of a glass bottle 13. The shape of the bottle about the mouth thereof is the usual shape employing the rounded bead 14 circumferentially around the bottle extending outwardly and downwardly from the top end C of the bottle, this end C being substantially flat over a limited portion therearound. As indicated in Fig. 3, the curvature of the dome B of the crown 10 is such that the paper liner 11 is held above this end zone C but is brought into intimate contact substantially over the entire area of the bead 14. When the crown is placed on the bottle and the lower corrugated end is compressed in to grip under the bead 14, the paper liner 11 is thus pulled down and around the bead snugly and compressed thereagainst and thus maintained.

In other words the sealing area between the crown and the bottle 13 is that between the outer face of the bead 14 and the inner face of the paper 11 brought into contact therewith. As above indicated, this particular portion of the bottle which forms this bead face is subject to little or no deformation as between any number of bottles molded so that crowns held to precise dimensions will uniformly effect a practically perfect seal with all bottles made in the same mold. On the contrary, the upper

end zone C with which crowns have heretofore been employed to effect a seal vary just enough to cause a large number of sealed bottles to be rejected on account of leakage. Little variations are bound to occur in this end zone C due to lack of control in the manufacturing process of the bottles.

The seal between the paper 11 and the outer surface of the bead 14 is further enhanced by 10 reason of the existence of the rubber derivative coating on the surface of the paper 11. This rubber coating backed up with the resilient paper comes into intimate contact with the glass surface over the microscopic hills and hollows that may be present. The rubber derivative is a good adhesive when brought into such intimate contact with the glass surface as is occasioned during the crowning operation.

The beverage bottles being sealed will be 20 sealed under thirty-two to forty pounds internal pressure. This pressure is exerted outwardly against the inner side of the crown 10 tending to bulge it outwardly. This would mean that if there be any bulging of the dome B, the distance 25 between the paper 11 and the bottle end C would tend to increase accordingly, particularly where the degree of curvature of the dome B was slight or even approached the flat state. The provision in the crown 10 in the present invention 30 of a dome B having a greater curvature than usual anticipates this outwardly bulging tendency giving in effect a "pre-bulged" crown. Should there be any travel outwardly of the dome B, a tighter seal is effected since the outward bowing of the dome B would tend to pinch 35 inwardly the side wall of the crown to effect a tighter seal against the bead 14. The seal would tend to be broken if it were maintained in the heretofore customary position across the zone 40 C since the bulging dome B would tend to lift from that area. In other words gas pressure within the bottle tends to increase and maintain the seal formed with the present invention rather than reducing that seal.

45 Referring to Fig. 3 again, it is to be noted that the crown 10 must not only seal against escape of liquid but also against escape of gas which may arise from the top of the liquid or be present between the liquid and the crown. 50 Should there be a tendency for escape of gas even in a minute quantity, the gas would have to travel between the paper 11 and over the end zone C of the bottle into a gradually decreasing clearance space therebetween. During the 55 inspection procedure, bottles are tested in one instance by turning them on end with the crown undermost and this, of course, brings the liquid against the paper 11 to flow into this V-section cavity, thereby in itself tending to form an additional seal against travel of gas from that cavity between the bead 14 and the paper 11. In other words the fact that the paper 11 is lifted and not in contact with the bottle end zone C and forms therewith a V-section cavity circumferentially around the bottle, introduces a further sealing effect.

While the invention has herein been shown and described in the one precise form, it is obvious that variations may be employed, particularly in the thickness not only of the paper but also of the coating, the exact dimensions, and other details in the crown itself, all without departing from the spirit of the invention and I therefore 70 do not desire to be limited to that precise form 75

beyond the limitations as may be imposed by the following claim.

I claim:

For sealing under gas pressure a frangible container having a substantially flat surface around its mouth normal to its axis, and a curved surface extending outwardly, downwardly and inwardly from said flat surface, the combination with said container of a container mouth enclosing metallic crown having a major top area outwardly convex to have the periphery of that area be substantially below the plane of said flat surface, a skirt integrally extending downwardly from said periphery outwardly convex in its upper portion at least to engage over said

15 container's curved surface, said skirt being corrugated to permit crimping under said inwardly curved surface portion, and a resilient liner in said crown following the curvature of said major area and extending down said skirt at least far enough to engage said container outwardly curved portion, whereby said crown in its sealed condition on said container has said liner in sealing contact over said curved container surface, and substantially free of contact with said flat surface to leave a V-section clearance between said liner and said flat surface with the apex of said section substantially at the outer peripheral portion of the flat surface.

ROBERT P. SMITH.
